UNITED STATES PATENT OFFICE.

BURNETT BUSH, OF KENNEDY, NEW YORK.

BAG-HOLDER.

957,652.

Specification of Letters Patent. Patented May 10, 1910.

Application filed August 31, 1909. Serial No. 515,392.

To all whom it may concern:

Be it known that I, BURNETT BUSH, a citizen of the United States, and a resident of Kennedy, in the county of Chautauqua 5 and State of New York, have invented a new and Improved Bag-Holder, of which the following is a full, clear, and exact description.

Among the principal objects which the 10 present invention has in view are: to provide a bag holder to hold the opening or top of a bag square and in an inclined position; to provide a holder for a bag which will yield to the variation in length caused 15 by the filling of the bag; and to provide a structure which is light, simple and efficient.

One embodiment of the present invention is disclosed in the accompanying drawings, in which similar characters of reference 20 denote corresponding parts in all the views, and in which—

Figure 1 is a perspective view of a bag holder constructed in accordance with this invention; Fig. 2 is an enlarged detail in 25 side elevation of a fragment of the guide arms and resilient carrying rods; and Fig. 3 is a front elevation of the bag holder illustrated in Fig. 1.

It is desirable to hold the mouth of a bag 30 while being filled so that the forward edge of the said mouth is depressed below the rear edge thereof. It is to satisfy this desire that I incline the holding arms 4—4. These are formed from suitable rod material, square or round, and bent downwardly to form the arms 4—4, as illustrated 35 at Figs. 2 and 3 of the drawings. From the ends of the arms 4—4 the rod is extended to form the guide members 5—5, which are extended through loops 6—6 40 formed in supporting rods 7—7. The supporting rods 7—7 are four in number and are mounted in a platform 8 to stand erect thereupon. The platform 8 may be provided 45 with thimbles 9—9, as shown in the drawings, to form sockets to receive the lower ends of the rods 7—7, extended under the platform, the under sections forming a bracing for the members constituting the 50 platform.

As stated, the guide members 5—5 are passed downward through the loops 6—6. The members 5—5 are bent to form in themselves the loops 10—10 which infold 55 the rods 7—7. By means of the loops 6—6 formed on the rods 7—7 infolding the guide

members 5—5, and the loops 10—10 formed on the guide members 5—5 infolding the rods 7—7, there is formed a sliding guided construction for the members 5—5 and the 60 arms 4—4. The members 5, 5, the arm 4 and loops 10, 10 on each side of the apparatus are formed from a single rod. Between the loops 6—6 and the loops 10—10 the rods are extended between the rods 7—7 65 and the members 5, 5 at each side of the platform. It is between the cross braces 11 and 12 thus formed that there is extended the expansion spring 13 which is rigidly attached to each of the side cross bracing 70 members. The operating of the spring 13 when in this position it is obvious, is to raise the members 5—5 and arms 4—4 connected therewith. If the bag be suspended from the arms 4—4 it is equally obvious that 75 it will be supported upon the springs 13—13. From the inner surface of the arms 4—4 are extended spurs 14—14, two or more of which are provided on each of the arms 4—4. The rods 7—7 are formed substantially as shown in Fig. 3 of the drawings, in such manner that when set in the platform 8 the tops of the rods 7—7 and the guide members 5—5 and arms 4—4 are extended away from each other as shown in 80 85 Fig. 3 of the drawings.

With an apparatus thus constructed the operation is as follows: The one side of the bag is extended under the one of the arms 4—4 and secured upon the spurs 14—14 90 there provided. The opposite arm 4 is then drawn into position where the opposite side of the bag may be extended under the back of the said arm 4 and inserted over the spurs 95 14—14. On releasing the arms 4—4 the rods 7—7 endeavor to assume their normal position, and in doing so draw against the mouth of the bag, drawing the sides thereof taut. In the usual construction the bag is a little 100 short of the length necessary to touch the platform 8, but in the beginning of the operation of filling the first partial load introduced into the bag increases the weight 105 sufficiently to extend the springs 13—13 to 105 allow the bag to touch and rest upon the platform. It will be understood that the weight of the bag and its contents is carried on the platform 8, and not on the arms 4—4. As the bag is filled the vertical height 110 of the sides is necessarily shortened, and it is to accommodate this that, as the strain is

transferred to the springs 13—13, these yield, permitting the mouth or edge of the opening to depress to accommodate the bulkier or shorter dimensions of the bag.

- 5 When the bag is filled the arms 4—4 are caused to approach each other to relieve the strain upon the mouth of the bag, and the edges thereof are raised out of contact with the spurs 14—14 and pass downward and
- 10 from under the arms 4—4. The bag is now filled and may be removed to give place to a succeeding bag. It will be understood that in this operation the position of the mouth of the bag wherein the forward end of the
- 15 same is depressed has facilitated the operator, particularly in loading the bag with certain forms of material which are dumped into the bag, such, for example, as grain.

- In some instances it is found desirable to
- 20 depress the arms 4—4 at the beginning of the operation of filling. It is to hold the arms in the depressed position that I have pivotally mounted at 16, upon the rods 5, the latches 15—15. The latches 15—15 pass
  - 25 under, in locking engagement, the loops 6—6 on the rods 7—7 to form guides for the rods 5—5. The latches hold against the tension of the springs 13—13. When sufficient material has been placed in the bags to steady
  - 30 the same, the latches 15 are released from engagement with the loops 6—6, lifting the said latches by the ends 17 thereof.

Having thus described my invention, what I claim as new and desire to secure by Letters Patent is:

1. A bag holder comprising a plurality of holding arms set in an inclined position depressed toward the front of the said holder; guide members integrally formed with said arms and depended therefrom and provided at the lower end with loops; a plurality of supporting rods mounted vertically and extended through said loops and being provided at the upper ends of said rods with loops infolding said guide members, said rods being formed to normally spread to separate the said holding arms each from the other; a platform to hold said supporting rods; cross braces extended between said loops; and expansion springs connecting the said cross braces to normally maintain the said holding arms in a raised position.

2. A bag holder comprising a plurality of holding arms set in an inclined position depressed toward the front of said holder; guide members integrally formed with said holding arms and depended therefrom; supporting rods for said arms slidably connected with said guide members; means for elevating the said arms upon the said supporting rods; and a latch mounted on the said arms to engage the said rods to hold the said arms in depressed position.

In testimony whereof I have signed my name to this specification in the presence of two subscribing witnesses.

BURNETT BUSH.
